(57) **CLAIM**

The ornamental design for a garage door seal, as shown and described.

DESCRIPTION

FIG. 1 is a front-right perspective view of a garage door seal showing our new design.

FIG. 2 is a rear perspective view thereof.

FIG. 3 is a front perspective view thereof.

FIG. 4 is a rear perspective view thereof.

FIG. 5 is a top perspective view thereof.

FIG. 6 is a bottom perspective view thereof.

FIG. 7 is a right side perspective view thereof.

FIG. 8 is a left side perspective view thereof; and,

FIG. 9 is an environmental perspective view thereof.

The evenly spaced broken lines depict portions of the garage door seal that form no part of the claimed design.

The garage door seal includes unevenly dashed lines in the various views, for example, FIGS. 3, 4, and 6, to depict surface curvature.

The drawings contain a symbolic break. The portion between the break lines forms no part of the claimed design.
